CONVERSION OF HYDROCARBON OILS

Joseph G. Alther, Chicago, Ill., assignor to Universal Oil Products Company, Chicago, Ill., a corporation of Delaware

Application May 12, 1938, Serial No. 207,432

3 Claims. (Cl. 196—48)

This is a continuation in part of my co-pending application, Serial No. 71,897, filed March 31, 1936 now abandoned. It is also related to my application, Serial No. 745,257, filed September 5 24, 1934 now abandoned, upon which application, Serial No. 71,897 is based, in part.

The invention relates to an improved process and apparatus for the pyrolytic conversion of hydrocarbon oils accompanied by the continuous reduction of their high boiling components to coke.

As a special feature of the invention, the total heat required for cracking and coking is imparted to the oil undergoing treatment prior to its introduction into the coking zone, the latter being unheated except for the heat carried by the oil undergoing treatment. This is accompanied by employing a furnace of the type invented by the present applicant and now known in the art as 15 an "equiflux" heater and also by separately heating the heavy oil charging stock for the system and intermediate liquid conversion products of the process in separate zones or cells of said equiflux heater. With a heater of this type I am 20 able to obtain high rates of heat input and thereby heat the oil to the high temperature required for its reduction to coke without allowing it sufficient cracking time in the heating coil to cause substantial coke formation and deposition in the 25 zone. By employing this form of heater and by separately heating the charging stock and intermediate liquid conversion products, I am able to continuously reduce the heavy liquid conversion products to coke in an unheated coking zone.

The coking zone is preferably of the continuous conveyor type which, in conventional practice, is fired to a high temperature. By eliminating the necessity of firing the coking zone I avoid contamination of the vaporous conversion products 35 with combustion gases. This method of operation is distinctly advantageous since it is extremely difficult to separate desirable light vaporous and gaseous hydrocarbons evolving in the cracking and coking operation from combustion gases with 40 which, according to conventional practice, they are mixed in any of the usual types of continuous coking systems.

I am fully aware of the fact that it is now common practice to crack relatively light and 45 relatively heavy oils in independently controlled heating coils and that this type of operation has been employed in cracking systems wherein the heavy liquid conversion products are reduced to coke. This type of operation has the advantage 50 of permitting more severe cracking of the rela-

tively light oil than that to which the heavy oil can be safely subjected without encountering coking difficulties in the heating coil. Advantages are taken of this fact in the process of this invention to obtain the heat required, for coking the 5 heavy oil, in excess of that supplied by the heavy oil heating coil.

The novelty of the invention does not reside in any single feature but rather in the advantageous and novel combination of the method of heating 10 employed, the two coil operation, and continuous coking attained without firing the coking zone.

The accompanying diagrammatic drawing illustrates one specific form of apparatus embodying the features of the invention and in which the 15 process of the invention may be conducted.

Referring to the drawing, charging stock for the process, preferably comprising an oil of relatively high-boiling characteristics, such as heavy crude petroleum, topped crude or other straight- 20 run or cracked residual oil, is supplied through line 1 and valve 2 to pump 3 by means of which it is directed through line 4 and valve 5 to heating coil 6, wherein it may be preheated to any desired temperature below that at which any ap- 25 preciable conversion thereof will occur, and the preheated oil is thence directed through line 7 to coil 8 wherein it is quickly heated, in the manner to be later more fully described, to a high cracking temperature, at the pressure, without 30 allowing it to remain in the heating coil for a sufficient length of time to permit any substantial formation and deposition of coke in this zone. The temperature to which the charging stock is 35 heated in coil 8 is, however, sufficient to effect 40 reduction of the non-vaporous components of the resulting conversion products to a heavy pitch-like residue and the heated products are discharged from heating coil 8 through line 9 and valve 10 into coking zone 11.

In order to accomplish heating of the charging stock under the desired conditions, which involve the use of relatively high rates of heat input and a relatively short time for the oil at cracking temperature in the heating coil, a fur- 45 nace of the general type illustrated at 44 is preferably utilized. The main structure of the specific form of the furnace here illustrated comprises side walls 45 and 46, a roof 47, a floor 48, and end walls which are not shown in the 50 particular view of the drawing here illustrated. The interior of the furnace is divided by means of a suitable wall 49, into two independently fired heating zones or cells 50 and 51. A fluid conduit 8 comprising, in the case here illus- 55

trated, a single vertical row of horizontally disposed tubes 52 is located within cell 50 midway between walls 45 and 49 and a separate fluid conduit 31 comprising, in the case here illustrated, two vertically parallel rows of horizontally disposed tubes 53 is located within cell 51 midway between walls 46 and 49. Adjacent tubes throughout fluid conduit 8 are connected at their ends in series by means of suitable return bends indicated in the drawing by the single lines 54 connecting the near end of adjacent tubes. Adjacent tubes in the two opposite rows of fluid conduit 31 are arranged in staggered formation and are connected at their ends in series by means of other suitable headers indicated by the lines 55. Separate combustion and heating zones 56 and 57 are located on opposite sides of fluid conduit 8 and controlled amounts of combustible fuel and air are supplied to each of these zones by means of suitable burners indicated at 58. Similar burners 58 also supply combustible fuel and air in regulated amounts to combustion and heating zones 59 and 60 located on opposite sides of fluid conduit 31. A plurality of burners 58, supplying fuel to each of the combustion zones 56, 57, 59 and 60, are preferably arranged in a row extending from one end to the other of each of the combustion zones so that a substantially continuous sheet of flame travels downward from near the tip of the burners to the lower portion of each of the combustion zones and preferably each of the burners is tilted slightly toward the adjacent wall of the furnace, as indicated in the drawing, so that the flames impinge upon each of the walls opposite the two fluid conduits, heating the same to a highly radiant condition. In this manner radiant heat is transmitted from the materials undergoing combustion and from the hot refractory furnace walls to opposite sides at each of the tubular elements of fluid conduits 8 and 31 whereby a high rate of heating is obtained in each of the fluid conduits.

In the particular case here illustrated, the combustion gases from both combustion and heating zones 50 and 51 commingle in the lower portion of the furnace beneath wall 49 and the commingled gases are directed through fluid heating zone 115 to a suitable stack, not illustrated. Two separate fluid conduits 6 and 29 are located within fluid heating zone 61. Each of the fluid conduits 6 and 29 comprise a plurality of rows of horizontally disposed tubes to which fluid heat is transmitted from the hot combustion gases passing thereover. A suitable checker wall or the like, such as indicated at 116, may be provided, when desired, in the path of flow of the combustion gases ahead of fluid heating zone 61 in order to secure better distribution of the gases in this zone.

60 The function of the several heating coils is to supply to the relatively light and relatively heavy oils undergoing treatment substantially all of the heat required for cracking and for reducing the heavy liquid conversion products to coke. It 65 should be understood that the invention is not limited to the specific flow of oils through the furnace here indicated so long as the streams of light and heavy oils supplied thereto are subjected to independently controlled heating conditions, both streams heated to a high cracking temperature and at least the heavy oil stream subjected to high rates of heat input and permitted only a short time in the heating coil after it has reached an active cracking temperature.

75 There are also other specific forms of heaters

which employ high rates of heat input to the oil, by utilizing direct and reflected radiant heat, which may be successfully utilized. However, the equiflux type of heater has been found most advantageous for this type of service and is the preferred form.

Coking zone 11, in the particular case here illustrated, comprises a continuous belt type conveyer 12, motivated by any suitable means, not illustrated in the drawing, and disposed within a suitable insulated housing 13. The belt of the conveyer is preferably constructed of suitable metal or metallic alloy and in the case here illustrated has upturned edges 14 for retaining the heavy non-vaporous conversion products which are discharged onto the belt at the inlet end of the coking zone through line 9 and which are reduced to coke during their passage through this zone. A layer of coke is thereby accumulated on the belt and is continuously removed at the discharge end of the coking zone by means of a suitable scraper 18. Provision is also made for directing a spray of cooling material, such as water, for example, onto the surface of the coke layer at the discharge end of the conveyer, which serves to cool the carbonaceous material and shrink the same away from the metallic conveyer belt, thereby assisting its removal. Introduction of the cooling material may be accomplished by means of line 15, valve 16 and one or a plurality of suitable nozzles indicated at 17. The coke removed from the conveyer, by means of scraper 18 or by cooling, or both, is discharged from the coking zone through a suitable outlet 19, communicating with a conveyor 20, by means of which the coke is discharged from the system. Preferably a portion of the outlet 19 and conveyor 20 is immersed in a suitable quenching medium, not shown, whereby the coke is cooled to a sufficiently low temperature to prevent combustion thereof upon being discharged to the atmosphere.

The vaporous conversion products supplied to the coking zone and the vapors evolved in this zone during the coking operation may be withdrawn therefrom through line 21 and directed through valve 22 to fractionation in fractionator 23, wherein their components boiling above the range of the desired final light distillate product of the cracking and coking operations are condensed, as reflux condensate. The reflux condensate may be withdrawn from the lower portion of fractionator 23 and directed through line 24 and valve 25 to pump 26 by means of which it is fed through line 27 and valve 28 to heating coil 29 and thence through line 30 into cracking coil 31, wherein it is heated at a relatively high rate to the desired cracking temperature, preferably at a substantial super-atmospheric pressure, the heated products being discharged from cracking coil 31 through line 32, valve 33 and line 9 to coking zone 11, wherein their high-boiling components are reduced to coke upon the continuous conveyer together with the high-boiling components of the heated products from heating coil 8, in the manner previously described.

By virtue of the additional heat imparted to the stream of conversion products issuing from coil 8 by commingling the same with the heated product discharged from coil 31, coking of the heavy liquid residue is accomplished on the continuous conveyer without supplying additional heat to the coking zone. The advantages of this practice have been previously outlined.

The vaporous products from coking chamber 11 will, in many cases, contain relatively small amounts of entrained or dissolved heavy liquids, such as tars, pitches and the like, of a high coke-forming nature, which are unsuitable for conversion in the relatively light oil cracking coil of the system and it is therefore entirely within the scope of the invention, although not illustrated, to provide a suitable tar separator, such 5 as a heat exchanger, partial condenser or a column provided with suitable baffles or rough fractionating means, wherein separation of such high-boiling materials from the lower boiling vaporous products may be accomplished, in which case the 10 high-boiling liquids removed from the vapors in the tar separating zone may be either removed from the system or returned, all or in part, to the heavy oil heating coil or direct to the coking zone, as desired. This particular feature has 15 been previously disclosed by the present inventor in connection with another type of coking operation and, for the sake of simplicity, it is omitted from the present drawing.

Fractionated vapors of the desired end-boiling 20 point, preferably comprising materials within the boiling range of motor fuel, of good antiknock value, and uncondensable gas, are removed from the upper portion of fractionator 23 and directed through line 34 and valve 35 to 25 condensation and cooling in condenser 36. The resulting distillate and uncondensed gases pass through line 37 and valve 38 to collection and separation in receiver 39. Distillate may be withdrawn from receiver 39 through line 42 and valve 30 33 43 to storage or to any desired further treatment. Regulated portions of the distillate collected in receiver 39 may, when desired, be recirculated by well known means, not shown in the drawing, to the upper portion of fractionator 23 to serve as a cooling and refluxing medium in 40 this zone for assisting fractionation of the vapors and to maintain the desired vapor outlet temperatures from the fractionator.

Gaseous products of the operation which remain uncondensed and undissolved in the distillate are removed from receiver 39 through line 45 40 and valve 41. Since this operation ordinarily produces a large amount of heavy olefinic gases, such as propene and butene, the gases recovered 50 from receiver 39 are ordinarily suitable as charging stock for a catalytic polymerization process and are preferably, although not necessarily, used as such.

The preferred range of operating conditions 55 which may be employed in an apparatus such as illustrated and above described may be approximately as follows: The heavy charging stock may be subjected in the relatively short-time heating coil to which it is supplied to a temperature, 60 measured at the outlet therefrom, of from 900 to 975° F., or more, preferably at a pressure which may range from substantially atmospheric up to a superatmospheric pressure of 150 pounds, or thereabouts, per sq. in. Preferably, to obtain 65 short time and high temperature, rates of heating of the order of 15,000 to 20,000 B. t. u./hour/sq. ft. of external heating surface are employed in coil 8. The heating coil to which the reflux condensate is supplied and wherein it is 70 preferably subjected to more severe cracking than the charging stock may employ an outlet conversion temperature ranging, for example, from 900 to 1000° F., preferably at a superatmospheric pressure measured at the outlet of the 75 heating coil, of from 150 to 800 pounds, or more,

per sq. in. The rates of heating employed in coil 31 may be and are preferably less than that in coil 8 but are ordinarily not less than approximately 10,000 B. t. u./sq. ft./hour. Preferably longer cracking time is provided for the light oil stream in coil 31 than that afforded the heavy oil stream in coil 8. The coking zone may be operated at a slight superatmospheric pressure sufficient to overcome the pressure drop through the succeeding fractionating, condensing, and collecting equipment, although higher pressures may be employed in this zone, when desired, and, when it is constructed to withstand higher pressures, the fractionating, condensing, and collecting portions of the system may employ pressures 10 substantially the same or somewhat lower than that utilized in the coking zone. Preferably, however, a slight subatmospheric or substantially atmospheric pressure is employed in the coking zone. This may be accomplished, for example, 15 by exhausting the gaseous products from the receiver of the system through a blower or steam-jet exhauster, not illustrated.

As an example of one specific operation of the process as it may be conducted in an apparatus 25 such as illustrated and above described, the charging stock is a residual oil produced by cracking and flash distillation. It has a gravity of approximately 10° A. P. I. and is supplied to the heavy oil coil from the flash chamber at a 30 temperature of approximately 750° F. It is quickly heated in the heavy oil coil to an outlet temperature of approximately 970° F. at a superatmospheric pressure of about 50 pounds per sq. in. at the inlet of the coil and substantially 35 atmospheric pressure at the coil outlet. The light oil stream from fractionator 23 is heated in the light oil cracking coil to an outlet temperature of approximately 1050° F. at a superatmospheric pressure of about 350 pounds per sq. in. and the 40 two heated streams are commingled and introduced into the surface of the continuous conveyor in the coking zone after the pressure on the light oil stream is released. The deposited coke is removed from the opposite end of the 45 conveyor, quenched and discharged from the system. The coking zone is operated at substantially atmospheric pressure. The vaporous products evolved in and supplied to the coking zone are cooled by indirect heat exchange with the light 50 oil stream being supplied to the light oil cracking coil, whereby heavy liquid particles, such as tars and the like, are removed from the vapors prior to their fractionation by the formation of the reflux condensate which comprises the light 55 oil cracking stock. The fractionation is controlled to give a distillate product of approximately 400° F. end boiling point. The reflux condensate supplied by the light oil cracking coil has a gravity of approximately 18 to 20° A. P. I. 60

The above described operation will produce per barrel of charging stock approximately 47% of 65 400° F. end-point gasoline of good antiknock value and about 65 pounds of petroleum coke suitable as domestic or industrial fuel. The remainder is chargeable principally to gas and loss.

I claim:

1. A process of cracking and continuous coking which comprises, quickly heating a residual oil to a temperature of the order of 900 to 975° F. 70 by passing the same through a heating coil subjected to high rates of heating by direct radiation from flames and hot refractory surfaces in a furnace without allowing the oil sufficient time in the heating coil to cause substantial coke for- 75

- mation and deposition therein, simultaneously and separately heating a lower boiling oil to a cracking temperature of the order of 950 to 1050° F., discharging resultant highly heated products of both heating steps onto the moving surface of a conveyer disposed within a coking zone and thereon effecting reduction of the high-boiling components of the heated products to coke without additional heating, removing said coke from the coking zone, separately removing vaporous hydrocarbons supplied to and evolved within the coking zone therefrom, fractionating the vapors to form a relatively clean condensate of lower boiling characteristics than the first mentioned oil, supplying said condensate as said lower boiling oil to the second mentioned heating coil, subjecting resultant fractionated vapors of the desired end-boiling point to condensation and recovering and separating the resulting distillate and uncondensed gases.
2. A process of cracking and continuous coking which comprises, subjecting a residual oil in a heating coil to rates of heating of the order of 15,000 to 20,00 B. t. u.'s per hour per square foot of external surface of said coil and thereby quickly heating the same to a temperature of the order of 900 to 970° F., simultaneously and separately heating a lighter hydrocarbon oil to a higher cracking temperature at substantial superatmospheric pressure under conditions of more prolonged cracking time in another heating coil employing lower rates of heating than the first-named coil but of the order of at least 10,000 B. t. u.'s per hour per square foot of external surface of said coil, discharging resultant highly heated products from both heating coils at substantially atmospheric pressure onto the moving surface of a conveyer disposed within a coking zone and thereon reducing their high-boiling components to coke solely by the heat contained in the products supplied thereto, continuously removing the accumulated coke from said conveyer and discharging the same from the coking zone, separately removing from the coking zone vaporous components of the heated products supplied thereto, fractionating the vapors to form a relatively clean condensate of lower boiling characteristics than the first mentioned oil, supplying said condensate as said lower boiling oil to the second mentioned heating coil, subjecting resultant fractionated vapors of the desired end-boiling point to condensation and recovering and separating the resulting distillate and uncondensed gases.
3. A cracking and coking apparatus which comprises, in combination, a heating coil disposed within a furnace to receive on both sides thereof radiant heat from flames and hot refractory surfaces of said furnace over which said flames are passed, a heating coil of materially greater length than that first mentioned and disposed within a furnace to receive on both sides thereof radiant heat from flames and hot refractory surfaces over which said flames are passed, means for passing a continuous stream of oil through the first mentioned heating coil, means for passing another stream of different hydrocarbon oil continuously through the second mentioned heating coil, means for separately controlling the rates of heating to which said separate streams are subjected and means for independently controlling the final temperature to which said separate streams are heated, a coking zone comprising a continuous conveyer disposed within an insulated housing, means for supplying highly heated products from each of said heating coils onto the surface of said conveyer, means for removing accumulated coke from said conveyer and discharging the same from the coking zone, means for separately removing vapors from the coking zone, a fractionator to which vaporous products from the coking zone are supplied, means for returning reflux condensate formed in said fractionator to the second mentioned heating coil and means for condensing and recovering the fractionated vapors.

JOSEPH G. ALTHER.
